[57] CLAIM

The ornamental design for a reconfigurable skull toy, as shown and described.

DESCRIPTION

FIG. 1 is a perspective view of a reconfigurable skull toy showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view of the design shown in FIGS. 1 through 7 in a reconfigured position;

FIG. 9 is a front elevational view thereof;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is another perspective view of the design shown in FIGS. 1 through 7 in a second reconfigured position;

FIG. 16 is a front elevational view thereof;

FIG. 17 is a rear elevational view thereof;

FIG. 18 is a top plan view thereof;

FIG. 19 is a bottom plan view thereof;

FIG. 20 is a right side elevational view thereof;

FIG. 21 is a left side elevational view thereof;

FIG. 22 is another perspective view of the design shown in FIGS. 1 through 7 in a third reconfigured position;

FIG. 23 is a front elevational view thereof;

FIG. 24 is a rear elevational view thereof;

FIG. 25 is a top plan view thereof;

FIG. 26 is a bottom plan view thereof;

FIG. 27 is a right side elevational view thereof;

FIG. 28 is a left side elevational view thereof;

FIG. 29 is another perspective view of the design shown in FIGS 1 through 7 in a fourth reconfigured position;

FIG. 30 is a front elevational view thereof;

FIG. 31 is a rear elevational view thereof;

FIG. 32 is a top plan view thereof;

FIG. 33 is a bottom plan view thereof;

FIG. 34 is a right side elevational view thereof; and,

FIG. 35 is a left side elevational view thereof.
